Primary Examiner — Mary Ann Calabrese(74) *Attorney, Agent, or Firm* — Sheppard, Mullin, Richter & Hampton LLP(57) **CLAIM**

The ornamental design for a table, as shown and described.

DESCRIPTION

FIG. 1 is a perspective, front view of a table showing my new design.

FIG. 2 is a top plan view of the table of FIG. 1.

FIG. 3 is a bottom plan view of the table of FIG. 1.

FIG. 4 is a left side view of the table of FIG. 1.

FIG. 5 is a right side view of the table of FIG. 1.

FIG. 6 is a front view of the table of FIG. 1; and,

FIG. 7 is a back view of the table of FIG. 1.

Broken lines in the figures show features that form no part of the claimed design.

1 Claim, 4 Drawing Sheets(56)
